UNITED STATES PATENT OFFICE.

JOHN KAEGI, OF PHILADELPHIA, PENNSYLVANIA.

ROLLER USED IN MANUFACTURING WALL-PAPER, &c.

SPECIFICATION forming part of Letters Patent No. 651,359, dated June 12, 1900.

Application filed October 28, 1899. Serial No. 735,081. (No model.)

To all whom it may concern:

Be it known that I, JOHN KAEGI, a citizen of France, residing at Philadelphia, county of Philadelphia, and State of Pennsylvania, have invented a certain new and useful Improvement in Rollers such as are Used in the Manufacture of Wall-Paper, &c., of which the following is a specification.

My invention relates to that class of printing-rollers on which the metal plates composing the design or pattern are secured for the purpose of printing wall-papers. The rollers generally in use for this purpose are made of wood and are therefore liable to warp or twist or even split with changes of temperature, &c. This necessitates not only the expense of a new roller, but the trouble of remounting the plates, which are, moreover, frequently injured by the operation.

The objects of my invention are, first, to provide a roller upon which the design-plates for printing or embossing wall-papers or other similar products are mounted and secured that will entirely prevent all risk of injury to the design through cracking or warping, and, second, to construct a roller that will not be affected by changes of temperature and which will be effective in its operation, simple in construction, and inexpensive in manufacture.

I attain the objects of my invention by the use and construction of a roller, as shown in the accompanying drawings; but I wish it understood that my invention is applicable to all or any of the various descriptions of rollers used for the purpose of printing or embossing wall-papers and other decorative material.

In the accompanying drawings, Figure 1 is a longitudinal sectional view showing the general construction of the roller. Fig. 2 is a side elevation of my invention, showing a few design-plates secured in position.

Similar letters of reference indicate the same parts in both figures of the drawings.

In Fig. 1, A shows the section of a brass tube of any size or diameter provided with separable or integrally-formed flanges B B at each end and forming a roller resembling a spool, the intervening space between the inner sides of the ends or flanges B B being completely filled up with plaster C, which when properly set and hardened is turned off

perfectly round in a lathe, or it may be suitably molded on, if found preferable to do so. 55 Its outer ends next to the flanges are gradually chamfered off to a slight bevel even with the edge of the flanges B B. a a a show in section the design-plates secured to the surface of the roller with small nails b b, the 60 space on the unoccupied surface of the plaster bed C between the design-plates and all other exposed surfaces being coated with a compound of shellac or other equivalent 65 resistant to the effects of water for the purpose of preserving the plaster bed C from all liability of absorbing moisture.

The diameter and thickness of the rollers and plaster are various and regulated by the nature and size of the design to be printed, 70 large patterns requiring greater circumferential area than smaller patterns, the thickness of the plaster bed C being regulated by size and strength required.

It will be apparent that a roller constructed 75 on or embracing the principles of my invention will entirely obviate the many disadvantages attending the use of rollers as hitherto in use.

Minor changes in the form, details, or construction may be resorted to without departing from the principle or sacrificing any of the advantages of my invention.

Having fully described the operation, construction, and objects of my invention, what 85 I claim as new, and desire to secure by Letters Patent, is—

A roller for printing or embossing wall-papers, comprising in its construction the combination of a metal roller A, having 90 flanges B, B, and the space between the inner sides of said flanges B, B, filled in with a composition of plaster, chamfered to a slight bevel even with the edge of said flanges B, its 95 outer surface coated with a suitable moisture-resistant, and design-plates nailed on the outer surface of the cylinder formed thereby, all substantially as shown and described for the purpose specified.

In testimony whereof I have hereunto affixed my signature in the presence of two subscribing witnesses.

JOHN KAEGI.
